(57) **CLAIM**

The ornamental design for a pet chew, as shown and described.

DESCRIPTION

FIG. 1 is a perspective view of a first embodiment of a pet chew illustrating our new design.

FIG. 2 is a front elevation view of the pet chew shown in FIG. 1.

FIG. 3 is a rear elevation view of the pet chew shown in FIG. 1.

FIG. 4 is a top plan view of the pet chew shown in FIG. 1.

FIG. 5 is a bottom plan view of the pet chew shown in FIG. 1.

FIG. 6 is a side elevation view of the pet chew shown in FIG. 1.

FIG. 7 is another side elevation view of the pet chew that is opposite the side elevation view shown in FIG. 6.

FIG. 8 is a perspective view of a second embodiment of the pet chew illustrating our new design.

FIG. 9 is a front elevation view of the pet chew shown in FIG. 8.

FIG. 10 is a rear elevation view of the pet chew shown in FIG. 8.

FIG. 11 is a top plan view of the pet chew shown in FIG. 8.

FIG. 12 is a bottom plan view of the pet chew shown in FIG. 8.

FIG. 13 is a side elevation view of the pet chew shown in FIG. 8, and

FIG. 14 is another side elevation view of the pet chew that is opposite the side elevation view shown in FIG. 13.

FIG. 15 is a perspective view of a pet chew illustrating a further new design.

FIG. 16 is a front elevation view of the pet chew shown in FIG. 15.

FIG. 17 is a rear elevation view of the pet chew shown in FIG. 15.

FIG. 18 is a top plan view of the pet chew shown in FIG. 15.

FIG. 19 is a bottom plan view of the pet chew shown in FIG. 15.

FIG. 20 is a side elevation view of the pet chew shown in FIG. 15; and,

FIG. 21 is another side elevation view of the pet chew that is opposite the side elevation view shown in FIG. 20.

The broken lines in the drawings illustrate portions of the pet chew which form no part of the claimed design.

1 Claim, 18 Drawing Sheets
